UNITED STATES PATENT OFFICE.

WILLIAM R. JOHNSON, OF CAMDEN, NEW JERSEY.

FIBER-CLEANING MACHINE.

1,224,648.

Specification of Letters Patent.

Patented May 1, 1917.

Application filed August 21, 1916. Serial No. 116,025.

To all whom it may concern:

Be it known that I, WILLIAM R. JOHNSON, a citizen of the United States, residing at Camden, in the county of Camden and State of New Jersey, have invented certain new and useful Improvements in Fiber-Cleaning Machines, of which the following is a specification.

My invention consists of improvements in fiber cleaning machines, and is especially serviceable for removing shives and other foreign material from wool, however, it will be understood that my invention may be used advantageously for other purposes.

In the opening and cleaning of raw fibrous material, the latter is usually fed into cleaning machines such for example as those known as "Willows", the material being tumbled and partially combed due to the rotation of a cylinder within a case, said cylinder generally having teeth thereon which mesh with teeth placed on the interior of the casing in which the cylinder rotates. The fibers are thereby opened or partially opened, and after they have passed through the machine, they are ejected from the casing and in some instances are compelled to pass between pressing or crushing rollers which are so designed as to crush any shives or foreign material so that it will freely drop from the fibers, the fibers passing outwardly either to another machine or to a receptacle for that purpose.

During this pressing or crushing action, some of the fibers also fall with the dirt and shives, which causes waste and loss to the manufacturer. In some instances, some of these fibers may be reclaimed, but since they are mixed with the dirt, it is an expensive process to reclaim these fibers.

One of the objects of my invention is to provide means for reclaiming the fibers such for example as fall during their progress through the pressing or crushing rolls or other means and returning them to the cleaning machine to again be passed through said rollers.

Another object is to so construct my invention that it will be applicable with practically all forms of cleaning machines and may be connected or built in with the cleaning machine.

A further object is to make my invention of simple construction so that it may be applicable to different types of machines, and

may be manufactured and installed at a reasonably low cost.

These objects, and other advantageous ends which will be described hereinafter, I attain in the following manner, reference being had to the accompanying drawings in which—

Figure 1 is an end elevation showing my invention in connection with two "Cone Willow" cleaning machines and crushing rollers designed to press the fibers as they pass from one machine to the other machine.

Fig. 2 is a plan view showing my invention in connection with a series of three cleaning machines of the "Cone Willow" type.

Fig. 3 is a sectional elevation of one of the "Cone Willows" constructed in accordance with my invention, and

Fig. 4 is a section taken on the line $a-a$ of Fig. 3.

Referring to the drawings, 1 is a casing which forms a housing for a frusto-conical cylinder 2 which is rotatably mounted in said casing and is provided with teeth 3 which mesh with teeth 4 on longitudinally extending side beams 5 in the casing.

A sieve or screen 6 is supported within the casing and serves to retain the fibers, but permits dirt, which collects due to the dusting of the cleaning action of the cylinder, to fall to the lower portion 7 of the casing where it may be removed from time to time.

The casing 1 has an inlet opening 8 near its narrow end, and an outlet opening 9 at its wide end through which the material after having been dusted, opened, and partially cleaned is ejected.

A frame 10 supports a series of pressing or crushing rolls 11 which are preferably fluted so that they will crush the shives or other foreign material without injuring the fibers. These rollers may be driven in any convenient manner so as to rotate and feed the fibers in the direction of the arrow as shown in Fig. 1 of the drawing into the inlet opening of another cleaning machine as shown in Figs. 1 and 2.

A perforated drum 12 is preferably located directly at the innermost end of the outlet opening 9 so as to receive the fibers as they are ejected by the cylinder 2. This drum acts as a preliminary collector for the

fibers, and acts also as a guide for the fibers toward the fluted rolls 11.

Hoppers 13 and 14 are positioned respectively below the rolls 11 and drum 12 and 5 form a receptacle so that the shives or other foreign material which falls during the progress of the fibers between the rolls, will drop therein. Furthermore, any of the fibers which fall will also be collected and 10 retained by said hoppers. The bottoms of the hoppers 13 and 14 are provided with openings to which are attached suction pipes 15 and 16.

These pipes 15 and 16 connect with a 15 main pipe 17 which extends upwardly and opens into the casing 1 as shown at 18 in Fig. 3. The large end of the cylinder 2 has a partition 19 which divides the cylinder into two compartments 20 and 21. The 20 compartment 21 is preferably closed by sheet material 22 which extends entirely around the cylinder, but the compartment 20 is open, the end of said compartment being limited by a spider 23 which acts as a 25 reinforcement and support for the end of the cylinder.

As illustrated, this spider 23 has four arms which respectively assist in supporting the ends of the lags 24 having the pins 30 3 thereon. This spider 23 is also provided with a central collar 25 through which the main shaft 26 of the cylinder extends.

A fan 27 is positioned within the compartment 20 and as illustrated has four 35 blades 28, each blade being in line with each of the arms of said spider and extend to the partition 19.

The rotation of the cylinder 2 and fan causes a suction of air inwardly through 40 the opening 18 and pipes 15, 16, and 17, so that any fibers which fall into the hoppers 13 and 14, are sucked into the compartment 20 and during the rotation of the cylinder, are again ejected outwardly through the 45 opening 9 to pass over the drum 12 and between the rolls 11. The dirt which falls into the hoppers 13 and 14 is heavier than the fibers, and hence remains at the extreme bottom of the hoppers where it may be 50 readily removed.

Any number of machines may be coupled together according to the condition of the fibers to be cleaned.

It will be understood that with my 55 invention, the cylinder acts both as means for opening and cleaning the fibers, while it is within the casing 1, and also acts to operate the fan to suck back into the casing 1, fibers which fail to properly go 60 through the crushing rolls or other cleaning mechanism.

My invention, therefore, is extremely efficient so that there is practically no waste or loss of fibers by their accidental falling 65 from the crushing rollers.

While I have described my invention as taking a particular form, it will be understood that the various parts of my invention may be changed without departing from the spirit thereof, and hence I do 70 not limit myself to the precise construction set forth, but consider that I am at liberty to make such changes and alterations as fairly come within the scope of the appended claims. 75

Having thus described my invention, what I claim as new and desire to secure by Letters Patent is:

1. The combination in fiber cleaning mechanism, of a unitary casing having a 80 movable cleaning member therein, suction producing means in said casing operatively connected to said member and operative in unison therewith, said casing having an outlet through which said member 85 ejects material after it has passed through said casing, a receptacle for receiving material after passing said outlet, and means forming a return passage between said receptacle and said suction producing means whereby material is sucked from said receptacle into the casing and again ejected out of said opening, substantially as described. 90

2. The combination in fiber cleaning 95 mechanism, of a unitary casing having a rotatable cleaning member therein, said member having a fan operatively connected thereto and mounted in said casing, said fan being rotatable in unison with said 100 member, said casing having an outlet through which said member ejects material after it has passed therethrough, a receptacle for receiving material after passing said outlet, and means forming a return 105 passage between said receptacle and the space within said casing occupied by said fan whereby said fan sucks material from said receptacle and again ejects it out of said opening, substantially as described. 110

3. The combination in fiber cleaning mechanism, of a unitary casing having a rotatable cleaning member therein, said member having a fan operatively connected thereto and mounted in said casing, said 115 fan being rotatable in unison with said member, said casing having an outlet opening through which said member ejects material after it has passed therethrough, additional cleaning means adjacent said outlet opening, a receptacle located below said additional cleaning means, and means forming a passage between said receptacle and the space within said casing occupied by said fan whereby the latter sucks material from said receptacle and again ejects it out of said opening, substantially as described. 120

4. The combination in fiber cleaning mechanism, of a casing having a rotatable 130

cleaning member therein, said member having a fan operatively connected thereto and mounted in said casing, an outlet opening through which said member ejects material
 5 after it has passed therethrough, a series of crushing rolls located adjacent said outlet opening, a receptacle located below said crushing rolls, and means forming a passage between said receptacle and the space
 10 within said casing occupied by said fan whereby said fan sucks material from said receptacle and again ejects it out of said opening, substantially as described.

5. The combination in fiber cleaning mechanism, of a casing having an inlet and an outlet opening, a rotatable shaft in said casing, a cylinder secured to said shaft within said casing, a fan operatively connected to said shaft and mounted within said casing,
 15 20 additional cleaning means adjacent said outlet opening, a receptacle located below said additional cleaning means, said casing having a third opening therein communicating with the fan, and means forming a passage
 25 between said receptacle and said third opening whereby material is sucked from said receptacle into the fan space and again ejected out of said opening, substantially as described.

30 6. The combination in fiber cleaning mechanism, of a casing having an inlet and an outlet opening, a rotatable shaft in said casing, a cylinder secured to said shaft within said casing, said cylinder being divided
 35 into two compartments, one of said compartments being closed to the interior of the casing, the other of said compartments being open to the interior of the casing, a fan rotatable in said latter compartment and oper-
 40 atively connected to said cylinder, additional cleaning means adjacent said outlet opening, a receptacle located below said additional cleaning means, said casing having an opening communicating with said open
 45 compartment, and means forming a passage

between said receptacle and said opening whereby material is sucked by said fan from said receptacle into the open compartment and again ejected out of said opening, sub-
 50 stantially as described.

7. The combination in fiber cleaning mechanism, of a unitary casing having an inlet and an outlet opening, a cylinder rotatable within said casing, a fan operatively connected to said cylinder and rotatable in
 55 unison therewith and mounted in the casing adjacent one end thereof, said end of the casing having an inlet suction opening, additional cleaning means adjacent said outlet opening, a receptacle located below said additional cleaning means, a pipe forming a
 60 65 passage between said receptacle and said suction opening in the casing, whereby the fibrous material is sucked from said receptacle into the fan space of said casing and again ejected out of said outlet opening, substantially as described.

8. The combination in fiber cleaning mechanism, of a casing having a rotatable cleaning member therein, said member having a fan operatively connected thereto and mounted in said casing, an outlet opening through which said member ejects material after it has passed therethrough, other
 70 75 cleaning means located adjacent said outlet opening, a receptacle located below said additional cleaning means, and means forming a passage between said receptacle and the space within said casing occupied by said fan whereby said fan sucks material from
 80 85 said receptacle and again ejects it out of said opening, substantially as described.

In testimony whereof I have signed my name to this specification in the presence of two subscribing witnesses.

WM. R. JOHNSON.
